(57) **CLAIM**

The ornamental design for a footwear protector, as shown and described.

DESCRIPTION

FIG. 1 is a top-right-rear view of a first implementation of a footwear protector showing the new design;

FIG. 2 is a top view thereof;

FIG. 3 is a bottom view thereof;

FIG. 4 is a left view thereof;

FIG. 5 is a right view thereof;

FIG. 6 is a front view thereof; and

FIG. 7 is a rear view thereof.

FIG. 8 is a top-right-rear view of a second implementation of a footwear protector showing the new design;

FIG. 9 is a top view thereof;

FIG. 10 is a bottom view thereof;

FIG. 11 is a left view thereof;

FIG. 12 is a right view thereof;

FIG. 13 is a front view thereof; and,

FIG. 14 is a rear view thereof.

The broken lines of FIGS. 1-14 showing portions of the footwear protectors form no part of the claimed design.

1 Claim, 8 Drawing Sheets
